UNITED STATES PATENT OFFICE

98,492

DESIGN FOR A DRESS OR SIMILAR ARTICLE

Claudia Block, New York, N. Y.

Application November 22, 1935, Serial No. 59,699

Term of patent 3½ years

To all whom it may concern:

Be it known that I, Claudia Block, a citizen of the United States, residing in the city of New York, county of New York, and State of New York, have invented a new, original, and ornamental Design for a Dress or Similar Article, of which the following is a specification, reference being had to the accompanying drawing, forming part thereof.

Figure 1 is a front perspective view of a dress, showing my new design.

Figure 2 illustrates the dress with the vestee removed.

Figure 3 illustrates the vestee.

The back of the dress is conventionally plain.

The characteristic feature of my design resides in the combination of the dress and vestee as shown, wherein the vestee is pleated and has attached thereto a pointed collar, said vestee passing through a slit near the collar portion of the blouse and extending to the waistline as shown.

I claim:

The ornamental design for a dress or similar article substantially as shown and described.

CLAUDIA BLOCK.
